STRIP TENSION DEVICE

Frank A. Kucera, Chicago, Ill., assignor to Union Special Machine Company, Chicago, Ill., a corporation of Illinois

Application April 30, 1934, Serial No. 723,242

10 Claims. (Cl. 112—152)

The present invention relates to new and useful improvements in strip tension devices for sewing machines, and more particularly to an improved tension device for applying tension to a binding strip, and the invention further relates to the provision of novel means under the control of the operator for applying or releasing the tension at will.

In the co-pending application of Herbert McK.

10 Carmichael, et al., Serial No. 636,764, filed October 7, 1932, there is shown and described a method of binding the edges of knitted fabric sections and the tension device shown and described herein is particularly adapted for such use wherein it is desirable to apply tension to the binding strip when stitching crosswise of the wales and wherein it is desirable to release the tension on the strip when stitching lengthwise of the wales. It is to be clearly understood, however, that the tension device, which is the subject of the present application, may be used with any type of strip where it is desired to apply tension thereto or to release the tension already applied thereto.

An object of the invention, therefore, is to provide a strip tension device which may be utilized for the above purpose and wherein the tension is released by cam actuating means under the control of the operator.

A further object of the invention is to provide a tension device wherein, by a slight adjustment, tension is normally applied or tension is normally released and wherein, in either case, means under the control of the operator are provided for releasing the tension in one case and for applying the tension in the other case.

A further object of the invention is to provide a strip tension device for use with sewing machines wherein, by a slight adjustment, the tension may be released by spring means or by a control member moved by the operator.

The above and other objects of the invention will in part be obvious and will be hereinafter more fully disclosed.

In the accompanying drawings:

45 Fig. 1 is a view showing the strip tension device applied to a sewing machine.

50 Fig. 2 is a side view of the tension device set for normally applying tension to the binding strip and showing, in dotted lines, the position of the parts when the operator releases the tension.

55 Fig. 3 is a rear view of the device shown in Fig. 2.

Fig. 4 is a detail sectional view of the tension device shown in Fig. 2.

Fig. 5 is a rear view of the tension device set for normally releasing the tension from the binding strip.

Fig. 6 is a fragmentary side sectional view of the device shown in Fig. 5 and showing in dotted lines, the position of the parts when the operator applies tension to the strip.

Fig. 7 is a sectional view taken along line 7—7 of Fig. 4.

The invention as illustrated is shown as applied to a sewing machine for binding fabric sections. It is often desirable in the attaching of a strip to a fabric section to place the strip under tension as it is fed to the stitching mechanism, or to release it in order to bring about a proper placing or releasing of the strip relative to the fabric for stitching. In the application of Herbert McK. Carmichael, et al., referred to above, a tension device is shown as applied to a machine of this type which is especially adapted for the stitching of a knitted binding strip to a knitted fabric. The tension is controlled by the operator and is releasable at will so that the fabric strip may move freely through the binder without any tension being applied thereto, or the tension may be applied to the binding strip so as to strain its movement and thus stretch the strip slightly as it is being stitched to the fabric.

The present invention has to do particularly with a tension device through which the strip passes on the way to the binder and to the means whereby the tension may be released or applied at will.

The tension device consists of two plates between which the fabric strip passes. One of these plates is carried by a bracket attached to a table while the other is mounted on the bracket so that it may be moved toward and away from the first named plate. Posts carried by the bracket extend through the movable tension device, and springs mounted on said posts and bearing against the movable tension member normally press said movable member against the fabric strip to create tension thereon. At the ends of the movable member are pins which extend through the bracket. At the rear of the bracket is a bar which is mounted for sliding movement vertically of the bracket. This bar has recesses formed in its inner face. There is a recess associated with each pin, and the pins have rounded ends and extend through the bracket into these recesses. The recesses at the upper and lower ends are gradually tapered to a flush position with the face of the bar thus producing cam actuating means. The spring moves the bar in one

direction and a treadle connected to the bar moves it in the other direction. When the bar moves to the extreme upper position through the action of the spring the lower cam becomes effected to contact with the pins and separate the tension plates. When it is moved to its extreme lower position by the actuation of the treadle then the upper cam becomes effected to separate the plates. A stop screw is provided which may be shifted from one set position to another for limiting the movement of the bar. This provides a means whereby the machine may be set so that the operator by depressing the treadle will release the tension and when the treadle is released the tension will be applied, or again the spring will lift the bar so as to release the tension and when the operator depresses the treadle the tension will be applied.

Referring more in detail to the accompanying drawings, there is shown, in Fig. 1, a sewing machine which includes an overhanging arm 10 and a needle head 11 in which the needle bar 12, carrying the needles 13, reciprocates. The material is held on the work support 14 by a presser foot 15 and is fed across the said work support by a feeding mechanism including a feed dog cooperating with the presser foot. Cooperating with the needles above the work support is a thread laying mechanism which includes a thread guide 16 and a cooperating thread hook 17 for laying the cover thread in loop form so that it is secured by the needle threads to cover the upper edge of the binding strip 18. Cooperating with the needles below the work support is a looper the thread of which joins the needle thread loops to cover the lower edge of the binding strip. The edge of the fabric is directed to the stitch forming mechanism by a guide 19 and the binding strip 18 passes through a binder 20 which folds the edges of the strip as it is fed beneath the presser foot. The above mechanism is clearly shown in the co-pending application of Herbert McK. Carmichael et al. above referred to, and no further description is considered necessary here. The binding strip passes through a tensioning device before entering the binder 20 and this tension device is mounted on the up-standing arm 21 of an angular bracket member, the laterally extending arm 22 of which is secured to the sewing machine table 23. The operator may readily control the operation of the tension device by a foot treadle 24 which is connected by a cord 25 extending through an opening in the table to an actuating member 26.

The particular details of the strip tension device will be more fully described and it is thought that the description will be better understood by referring to Figs. 2 to 7. A tension plate 27 is mounted on the arm 21 of the bracket in fixed parallel relation thereto by the spaced posts 28 the ends of which are threaded to engage the bracket arm 21. An additional tension plate 29 is carried by the posts 28 for movement relative to the fixed plate 27. The posts 28 carry coil springs 30 which normally urge the movable plate 29 toward the fixed plate 27 and the tension exerted by the springs on the plate 29 may be adjusted by nuts 31 carried by the outer ends of the posts against which the ends of the springs abut. The plate 29 is longer than the plate 28 and pins 32, 33 are carried by the protruding ends thereof. These pins 32 pass through openings in the bracket arm 21 and are provided with rounded ends 32a, 33a which extend slightly beyond the opposite side of the bracket arm.

A shiftable plate 34 is mounted on the opposite side of the bracket arm 21 by means of screws 35 which extend through longitudinal slots 37 in the plate 34 and which are provided with stop shoulders 36 which limit the movement thereof into the bracket arm and so permit a free shifting movement of the plate longitudinally but not laterally of the bracket arm 21. The shiftable plate 34 is provided with a lateral extension 38 to which the cord 25 is connected. A spring 39 having one end thereof connected to the upper end of the bracket arm 21 and having the other end thereof connected to the upper end of the plate 34 normally holds the plate 34 in a raised position.

It will thus be seen that, by depressing the foot treadle 24, the plate will be caused to descend but, upon release of the treadle, the spring 39 will return the plate to its normal raised position. At one side of the plate 34 and intermediate the slots 37 is a cut out portion 40 which permits the insertion of a set screw 41 in either of two threaded openings 42, 43 in the bracket arm 21, and this set screw serves as a stop for the plate or bar 34. The inner face of the plate 34 is provided with longitudinal recesses 44, 45 into which the rounded ends of the pins 32, 33 respectively extend as shown in Fig. 4. The upper and lower edges of the recesses are tapered to a position flush with the inner face of the plate 34 so as to provide cam surfaces for actuating the pins in a manner to be hereinafter fully described.

As shown in full lines in Figs. 2, 3 and 4, the set screw 41 is in the lower position, that is, in the threaded opening 43, and the rounded ends of the pins 32, 33 do not contact the surface of the recesses 44, 45 respectively so that the tension plate 29 is urged inwardly in tension applying position against the strip 18 which passes between the two tension plates. In this position the treadle 24 is released and the spring 39 holds the bar 34 in a raised position. When the operator depresses the treadle 24, the bar 34 is moved to the dotted line position, shown in Figs. 2 and 3 and the upper tapered cam surfaces of the recesses 44, 45 contact the rounded ends 32a, 33a, of the pins 32, 33 respectively and force the pins outwardly whereby the tension plate 29 is shifted away from the strip 18, as shown in dotted lines in Fig. 2, in order to release the tension on the strip.

In Figs. 5 and 6, it will be noted that the set screw 41 is shown in the upper threaded opening 42 and in this position, as shown in full lines in Figs. 5 and 6, the tension plate 29 is normally held in tension releasing position away from the strip 18 because the spring 39 holds the bar 34 in a raised position so that the ends of the pins are forced outwardly by the lower cam surfaces of the recesses 44, 45, as shown in Fig. 6. When the operator depresses the treadle 24, the bar 34 is caused to assume the position, shown in dotted lines in Fig. 6, wherein the tension plate and pins 32, 33 are forced inwardly by the springs 30 and the ends of the pins may extend into the recesses 44, 45, so that tension is applied to the strip 18.

From the foregoing description, it will be seen that the outer or movable tension plate 29 is shifted in a direction at right angles to the longitudinal axis of the bracket arm 21 by means of the bar or plate 34 which is moved in a direction which is parallel to the longitudinal axis of the bracket arm 21. As pointed out above, the

tension device may be manually set to either normally apply tension to the strip, or to normally release the tension from the strip depending upon which of the openings 42, 43, that the setscrew 41 is placed, but in either case, the operation of the tension plate 29 through the pins 32, 33 is caused by the movement of the bar 34 which is directly controlled by the operator through the treadle 24 and connecting cord 25. It will thus be seen that the present invention provides a strip tension device which may be set, in the first instance, to normally apply tension to a strip or, in the second instance, to normally release the tension from the strip and the type of work or desire of the operator will determine in which position the device should be set. In either instance, cam actuating means on a slideable operating plate under the control of the operator are provided for releasing the tension or applying tension depending upon which position the device sets manually.

Of course, minor changes in details of construction and arrangement of parts may be made without departing from the scope of the invention as set forth in the appended claims.

Having thus fully described my invention, what I claim as new and desire to secure by Letters Patent, is:—

1. A sewing machine including, in combination, a stitch forming mechanism, a guide for directing a binding strip about the edge of the fabric and to the stitch forming mechanism, and a tension device through which the binding strip passes, said tension device comprising a supporting bracket, a fixed tension plate carried by said bracket and across which the binding strip passes, a tension plate carried by said bracket and movable toward and away from said fixed tension plate, spring means for normally forcing said movable plate toward said fixed plate to apply tension to the strip, a treadle controlled operating member carried by said bracket and movable thereon, and cam means associated with said operating member for shifting said movable tension plate to release the tension on the strip.

2. A sewing machine including, in combination, a stitch forming mechanism, a guide for directing a binding strip about the edge of the fabric and to the stitch forming mechanism, and a tension device through which the strip passes, said tension device comprising a supporting bracket, a fixed tension plate carried by said bracket, a tension plate movable toward and away from said fixed tension plate, pins carried by said movable tension plate extending through said supporting bracket, spring means for normally forcing said movable tension plate to apply tension to the strip, an actuating plate mounted on the opposite side of said bracket for movement relative thereto, and cam means associated with said plate for engaging the free ends of said pins for shifting said movable tension plate to release the tension on said strip.

3. A sewing machine including, in combination, a stitch forming mechanism, a guide for directing a binding strip about the edge of the fabric and to the stitch forming mechanism, and a tension device through which said strip passes, said tension device comprising a supporting bracket, a fixed tension plate carried by said bracket and over which the strip passes, a tension plate carried by said bracket and movable toward and away from said fixed tension plate, posts extending through both of said tension plates, springs carried by said posts and bearing against said movable tension plate for normally forcing the same

toward said fixed tension plate to apply tension to the strip, pins secured to said movable tension plate and extending entirely through said bracket, an actuating plate secured to the opposite side of said bracket for limited movement longitudinally thereof, cam faced recesses on the inner face of said actuating plate and adapted to cooperate with the free ends of said pins, and means for shifting said actuating plate whereby to cause said cam faces to engage the ends of said pins to shift said movable tension plate.

4. A sewing machine including, in combination, a stitch forming mechanism, means for directing a strip thereto, and a tension device through which said strip is adapted to pass, said tension device comprising a supporting member, a fixed tension plate carried by said supporting member, a movable tension plate carried by said supporting member, spring means for normally forcing said movable tension plate toward said fixed tension plate to apply tension to said strip, an operating bar, means including a pin and slot connection for mounting said bar on said supporting member for movement in a direction at right angles to the direction of movement of said movable tension plate, and means operable upon the movement of said operating bar for shifting said movable tension plate.

5. A sewing machine including, in combination, a stitch forming mechanism, means for directing a strip thereto, and a tension device through which said strip is adapted to pass, said tension device comprising a supporting member, a fixed tension plate carried by said supporting member, a movable tension plate carried by said supporting member, spring means for normally forcing said movable tension plate toward said fixed tension plate to apply tension to said strip, an operating bar having cam surfaces thereon, means including a pin and slot connection for mounting said operating bar on said supporting member for movement relative thereto, and means cooperating with the cam surfaces on said operating bar for shifting said movable tension plate away from said fixed tension plate to release the tension on the strip.

6. A sewing machine including, in combination, a stitch forming mechanism, means for directing a strip thereto, and a tension device through which said strip is adapted to pass, said tension device comprising a vertical supporting member having a threaded opening, an operating bar secured to said supporting member for movement relative thereto, said bar having a cut out portion registering with said threaded openings, a stop screw adapted to be inserted in said opening, a fixed tension plate carried by said supporting member, a movable tension plate carried by said supporting member, spring means for normally forcing said movable tension plate toward said fixed tension plate to apply tension to said strip, cam faced recesses on said operating bar, a spring for normally holding said operating bar in a raised position with the edge of said cut out portion abutting against said screw, pins secured to said movable tension plate and extending through said supporting member and into said recesses on said supporting bar when said screw is in said opening with the bar raised to abut against said screw, and means for lowering said operating bar to cause the cam faces on said operating bar to engage the free ends of said pins to force said movable tension plate away from said fixed tension plate whereby to release the tension on said strip.

7. A sewing machine including, in combination, a stitch forming mechanism, means for directing a strip thereto, and a tension device through which said strip is adapted to pass, said tension device comprising a vertical supporting member having a threaded opening, an operating bar secured to said supporting member for movement in a single plane relative thereto, said bar having a cut out portion registering with said threaded opening, a stop screw adapted to be inserted in said opening, a fixed tension plate carried by said supporting member, a movable tension plate carried by said supporting member, spring means for normally forcing said movable tension plate toward said fixed tension plate to apply tension to said strip, cam faced recesses on said operating bar, a spring for normally holding said operating bar in a raised position with the edge of said cut out portion abutting against said screw, pins secured to said movable tension plate and extending through said supporting member and bearing against said operating bar when said screw is in said opening with the bar raised to abut against the screw, and means for lowering said operating bar to permit the free ends of said pins to extend into said recesses whereby said movable tension plate is shifted toward said fixed tension plate to apply tension to said strip.
8. A sewing machine including, in combination, a stitch forming mechanism, means for directing a strip thereto, and a tension device through which said strip is adapted to pass, said tension device comprising a supporting bracket, a fixed tension plate carried thereby and across which said strip passes, a movable tension plate carried by said bracket and associated with said fixed tension plate, springs for forcing said movable tension plate toward said fixed tension plate for applying tension to said strip, a control bar shiftable on said bracket and having spaced cam actuating devices, a device connected to said movable tension plate and with which one of said cam actuating devices may contact to release the tension on the strip, a spring for moving said control bar in one direction, and a stop for limiting the movement of said bar, said stop being movable to different set positions whereby one or the other of said cam actuating devices is rendered effective for releasing the tension on the strip.
9. A sewing machine including, in combination, a stitch forming mechanism, means for directing

a strip thereto, and a tension device through which said strip is adapted to pass, said tension device comprising a supporting bracket, a fixed tension plate carried by said bracket and associated with said fixed tension plate, springs for forcing said movable tension plate toward said fixed tension plate for applying tension to said strip, a control bar shiftable on said bracket and having spaced cam actuating devices, a device connected to said movable tension plate and with which one of said cam actuating devices may contact to release the tension on the strip, a spring for moving said control bar in one direction, and a stop for limiting the movement of said bar, said stop being movable to different set positions whereby one or the other of said cam actuating devices is rendered effective for releasing the tension on the strip, and said cam actuating devices being so disposed that when said stop is in one set position the spring for moving said control bar becomes effective for releasing the tension on the strip and when said stop is in the other set position said spring becomes effective for permitting the tension to be applied to said strip.

10. A sewing machine including, in combination, a stitch forming mechanism, means for directing a strip thereto, and a tension device through which said strip is adapted to pass, said tension device comprising a vertically arranged supporting bracket, a fixed tension plate carried by said bracket and movable toward and away from said fixed tension plate in a horizontal direction, an operating bar secured to the opposite side of said bracket and movable longitudinally of said bar in a direction at right angles to the movement of said movable tension plate, means for setting said operating bar in a position wherein said movable tension plate is normally in tension applying position or in a position wherein said movable tension plate is normally in tension releasing position, cam means operable upon the downward movement of said operating bar for shifting said movable tension plate away from said fixed tension plate when normally in tension applying position, and spring means operable upon the downward movement of said operating bar for shifting said movable tension plate toward said fixed tension plate when in normally tension releasing position.

FRANK A. KUCERA. 50
